UNITED STATES PATENT OFFICE.

ELMER BROBERG, OF ROCKFORD, ILLINOIS, ASSIGNOR TO ELCO TOOL AND SCREW CORPORATION, OF ROCKFORD, ILLINOIS, A CORPORATION OF ILLINOIS.

FALL SUPPORT FOR DESKS AND THE LIKE.

Application filed September 5, 1925. Serial No. 54,655.

This invention relates in general to furniture and has more particular reference to a fall support such as is used on a writing desk or cabinet or on any article of furniture of this character.

The primary purpose of my invention is to provide an improved fall support characterized by the use of slides adapted to be projected from the desk, case or cabinet to an extended position in which to support the fall when it is swung down, and by the provision of a novel connection between the fall and slides for projecting and retracting the latter when the fall is swung down and up.

Another purpose is to so construct the connections between the fall and slides as to permit quick and easy installation thereof after the writing desk or cabinet has been completely assembled and finished, and also to permit quick and easy removal of said connections at will for refinishing or for any other reason.

Still another purpose is to provide connections of the character described so constructed that they will occupy but minimum space and will not be obstructive or unsightly and which will not interfere with the free use of the writing top of the desk formed by the fall and fall bottom.

I have also aimed to provide improvements of the character described so constructed as to enable manufacture thereof at a comparatively low cost.

Referring to the drawing:

Figure 1 is a fragmentary perspective view of a fall support embodying my invention applied to a writing desk; and

Fig. 2 is an enlarged vertical section showing the connection between one of the fall-supporting slides and the link which provides the connection between said slide and the fall proper.

It will be understood that my improvements may be applied to any article of furniture having a hinged fall or lid such, for example as is used on a writing desk. In illustrating my invention I have shown in a fragmentary way only one end or side of a conventional writing desk, it being understood that the construction is duplicated at the opposite end. The well known parts comprise a case or cabinet having an end 3, a fall bottom 4, and a fall or lid 5 hinged to the fall bottom at 6 and adapted to be

swung down and up, to and from the operative position shown.

In each end of the case, just beneath the fall bottom, is suitably mounted a slide 7 adapted to be slid lengthwise from an inoperative position to the extended position shown in Fig. 1 in which the front end of the slide underlies and supports the fall in its down position. My invention is in the novel form of connection between the fall and slide, whereby the slide will be projected and retracted automatically by the lowering and raising of the fall.

This connection which applies to a slide at each end of the fall, as above mentioned, comprises a link designated generally by 8 pivotally connected at its forward end at 9 to the fall through means of a suitable bracket 11, and having a downwardly turned rear end 12 which extends through a slot 13 in the adjacent end of the fall bottom 4 and is detachably connected to the slide 7. The link 8 is preferably of flat metal stock and disposed with its flat plane vertically in close proximity to the end 3 and is, furthermore, attachable to and detachable from the slide 7 by movement in the plane thereof. As a result of this the slot 13 may be quite narrow so as to prevent pencils, pens and the like from falling through, and the link 8 is out of the way and unobtrusive. The detachable connection between the link and slide, which characterizes my invention, is effected as follows: A sheet metal plate 14 is set into the top of the slide 7 and secured thereto as by means of screws 15. This plate has an opening 16 across which extends a pin 17, the plate opening and pin being formed by a stamping operation. The down-turned end 12 of the link is slotted longitudinally as at 18 to provide resilient fingers 19 adapted to make a snap connection with the pin 17. To facilitate this connection said pin may be slightly rounded and the fingers 19 may be notched or recessed as at 21 for the reception of the pin and for locating the link thereon and providing a pivotal connection therewith. The slide is notched or recessed at 22 to provide clearance for the end of the fingers 19.

It will be manifest from the foregoing that the desk or cabinet may be completely assembled and finished before the link 8 is applied. After installation of the link by connection of the bracket 11 to the fall, the

slotted or bifurcated end will be pressed down over the pin 17 into a snap connection therewith, thus pivotally connecting the link to the slide. Since the function of the link is merely to move the slide 7 forward and backward the connection of the kind disclosed is sufficient and thoroughly practical. Furthermore, this provides a quick detachable connection so that the link may be removed at will as is sometimes required for refinishing purposes or for replacement in case of breakage.

It is believed that the foregoing conveys a clear understanding of the objects prefaced above and it should be apparent that the construction disclosed is so designed that the few parts may be produced by stamping operations at a comparatively low cost.

20 I claim:

1. A device of the character described comprising a link arranged to be pivotally connected at one end to a desk fall and to extend to a fall-supporting slide to operate 25 the latter, and a plate arranged to be fastened to the slide and having a part providing for a quickly attachable and detachable pivotal connection between the link and plate, the link being arranged to operate through a narrow slot in the fall bottom and the said connection being such that the attachment or detachment of the link may be accomplished entirely through the slot.

35 2. A device as set forth in claim 1, wherein the plate arranged to be attached to the slide to which the link is to be detachably connected has an opening therein for the reception of the end of said link, and provides a pivot pin for the link as an integral part of the plate extending across said opening.

3. A device as set forth in claim 1 wherein the plate has an opening therein for the reception of the end of the link, one side of the opening being arranged to cooperate with a conformed part of the link to provide a pivotal detachable connection between the parts.

50 4. A device of the character described comprising a link arranged to be pivotally connected at one end to a desk fall and to extend to a fall-supporting slide to operate

the latter, and a plate arranged to be fastened in a substantially horizontal position on the top of the slide and to be detachably engaged by the free end of said link, the link being flat and narrow and having the free end thereof presented edgewise in a substantially vertical plane to the plate so as to permit operation thereof through a narrow slot in the fall bottom, and the free end of the link being conformed for quick and easy detachable connection with a part of the plate made to cooperate therewith, the connection being such that the movement of the link only in the edgewise plane thereof permitted by the narrow slot in the fall bottom is sufficient to accomplish the attachment or detachment of the link to and from the plate.

5. A plate for detachably connecting a fall supporting link with its slide arranged to be fastened to the slide and having a narrow slot therein for the edgewise reception 75 of the end of a flat narrow link for pivotally and detachably connecting the link with the plate.

6. A device of the character described comprising an elongated flat narrow link 80 arranged to be pivotally connected at one end to a desk fall and curved downwardly in the edgewise plane thereof at the other end for passage through a narrow slot provided in a fall bottom and connection with 85 a fall-supporting slide, and a plate arranged to be fastened in a horizontal position on the top of the slide and to be detachably engaged by the free end of said link, said link being longitudinally slotted 90 inwardly from the free end thereof to provide by the bifurcation a pair of elongated resilient fingers and having a bearing opening provided therein intersected by the slot and near the open end thereof, and a pivot pin 95 provided on said plate arranged to be entered through the open end of said slot for reception in the bearing opening, the connection being such that movement of said link only in the edgewise plane thereof as permitted 100 by the narrow slot in the fall bottom is sufficient to accomplish the attachment or detachment thereof to and from the plate.

In witness of the foregoing I affix my signature.

ELMER BROBERG.
